Atlys.

UNITED STATES PATENT OFFICE.

JOHAN C. BERGMAN, OF ROCKFORD, ILLINOIS, ASSIGNOR TO ROCKFORD NOVELTY FURNITURE COMPANY, OF ROCKFORD, ILLINOIS, A CORPORATION OF ILLINOIS.

LOUD-SPEAKER HORN.

Application filed April 9, 1926. Serial No. 100,782.

This invention relates to an amplifier horn especially designed for use with radio loud speaker units but, of course, capable of application to about equal advantage in connection with phonograph reproducers.

The principal object is to provide a horn particularly well adapted for mounting in cabinets in the confined space usually available which has better acoustic properties than those heretofore provided.

With the foregoing object in view, the invention provides, in effect, a horn within a horn in reversed relation so as to make a longer air column available and thus increase the volume and produce truer tones, the arrangement also giving rise to a reflection of the sound from the source whereby the echo is transmitted. A horn embodying these features, in addition to being simple and economical in construction, is thoroughly practical since it lends itself to installation in a variety of cabinets by reason of its compactness and peculiarly adaptable form.

The invention is illustrated in the accompanying drawing, wherein—

Fig. 1 is a front view of a horn embodying the novel features above referred to; and

Fig. 2 is a longitudinal vertical section taken on the line 2—2 of Fig. 1 looking in the direction of the arrows.

The horn of my invention, as illustrated by the present preferred embodiment, comprises a main horn or bell 5 and a secondary horn or bell 6 preferably within the same and reversed in direction with respect thereto. Both horns are preferably entirely of wooden construction for best tone qualities. The main horn 5 is of a truncated form and has a relatively thick back wall 7 with side walls 8 and 9 and top and bottom walls 10 and 11 extending in outwardly divergent relation thereto maintaining an approximately rectangular section throughout, as shown. The secondary horn 6 is built upon the bottom wall 11 of the main horn with this wall forming one of the side walls of the secondary horn. The term "side" as here used, and as used in the claims, should be taken merely as distinguishing from end walls such as the back wall 7 of the main horn 5 or the back wall 12 of the secondary horn 6. The back wall 12 of the secondary horn 6, it will be noted, is relatively thick as are also the side walls 13 and 14. The

remaining wall 15, however, is comparatively thin. The purpose in providing the side walls of the main horn of appreciable thickness, as well as the back and side walls of the secondary horn, is to eliminate any tendency for any unpleasant vibrations being set up within the usual vibration periods of the sounds transmitted. The wall 15 is provided comparatively thin so as not to restrict the sound passage and no objectional vibrations are apt to be set up at this source in view of the fact that all of the walls joining therewith are comparatively heavy. From the description thus far it will be apparent that the area of the section of the sound passage increases gradually from the small end of the secondary horn to the large end thereof and thence from the small end of the main horn to the large end of the latter. The large end of the secondary horn is approximately of the same width as the small end of the main horn and, as will be apparent from the drawing, is of approximately half the height.

By virtue of the arrangement of the secondary horn 6 within the main horn 5 directed toward the rear wall 7, there is made available an air column of approximately the aggregate length of the two horns while only the overall length of the main horn has to be taken into consideration in the mounting of the horn in a cabinet. The increased air column afforded gives greater volume and truer tones. Harshness of tone is entirely eliminated. Overtones incident to vibration of the material of the transmitting medium are avoided by providing the horn entirely of wooden construction with the proper wall thicknesses, as above mentioned. The sound originating at the small end of the secondary horn is reflected at the back wall 7 of the main horn and the echo is transmitted. An opening 16 is provided in the bottom wall 11 of the main horn communicating with the small end of the secondary horn, as shown. A loud speaker unit 17 of any one of the usual or preferred types is mounted at the opening 16, as shown. A plate 18 for supporting the unit may be secured to the outside wall 11 at the opening 16.

It is believed that the foregoing description conveys a clear understanding of the invention and of its purposes and advantages

so that anyone skilled in the art to which the invention relates will appreciate the possible applications thereof.

I claim:

5. 1. A horn of the character described comprising a main horn having a back wall and diverging side walls extending outwardly therefrom, and a secondary horn within the main horn in reversed relation thereto so as to be directed toward the back wall thereof and having a side wall in common with the main horn, said wall having an opening therethrough leading into the small end of the secondary horn.
15. 2. An amplifier horn comprising a main horn having a back wall and diverging side walls extending outwardly therefrom, and a secondary horn built within said main horn in reversed relation thereto so as to be directed toward the back wall thereof, said secondary horn having one of its side walls formed by one of the side walls of said main horn.
25. 3. An amplifier horn comprising a main horn having a back wall and diverging side walls extending outwardly therefrom, and a secondary horn disposed within said main horn on one side wall thereof and in reversed relation thereto so as to be directed 30 toward the back wall thereof, there being an opening in the side wall of said main horn communicating with the small end of said secondary horn to provide a place for

mounting a reproducer unit transmitting into the small end of said secondary horn. 35

4. An amplifier horn comprising a main horn of a truncated bell form having a back wall and diverging side walls extending outwardly therefrom, and a secondary horn built onto one of the side walls of said main horn using said side wall as one of the side walls of said secondary horn, said secondary horn being reversed in relation to said main horn and directed toward the back wall thereof, the small end of said secondary horn being arranged to have communication with a source of sound, and the large end thereof communicating with the small end of said main horn.

5. An amplifier horn comprising a main bell having a thick back wall and thick side walls diverging outwardly therefrom, and a secondary bell built within said main bell on one of the side walls thereof using said wall as one of the walls of said secondary bell, said secondary bell having a thick back wall and thick diverging lateral walls, the remaining wall being relatively thin and extending with said lateral walls in diverging relation from said last mentioned back wall inwardly relative to said main bell toward the back wall of the latter. 55 60

In witness of the foregoing I affix my signature.

JOHAN O. BERGMAN.
